US0D1045795S

(12) **United States Design Patent** (10) **Patent No.:** **US D1,045,795 S**
(45) **Date of Patent:** **** Oct. 8, 2024**

(54) **BATTERY TRAY**

(71) Applicant: **THE NOCO COMPANY**, Glenwillow, OH (US)

(72) Inventors: **Jonathan Lewis Nook**, Gates Mills, OH (US); **James Richard Stanfield**, Peoria, AZ (US); **Derek Michael Underhill**, Tempe, AZ (US)

(73) Assignee: **The Noco Company**, Glenwillow, OH (US)

(**) Term: **15 Years**

(21) Appl. No.: **29/705,701**

(22) Filed: **Sep. 13, 2019**

Related U.S. Application Data

(63) Continuation of application No. 16/564,758, filed on Sep. 9, 2019, now Pat. No. 11,251,507.

CLAIM

The ornamental design for a battery tray, as shown and described.

DESCRIPTION

FIG. 1 is an exploded perspective view of a battery tray; FIG. 2 is an exploded front view thereof, the rear view being a mirror image of FIG. 2;

FIG. 3 is an exploded right side view thereof, the left side being a mirror image of FIG. 3;

FIG. 4 is a perspective view of a battery tray;

FIG. 5 is a front view thereof, the rear view being a mirror image of FIG. 5; and,

FIG. 6 is a right side view, the left side being a mirror image of FIG. 6.

The broken lines shown in the drawings depict environmental structure or portions of the article that form no part of the claimed design.

1 Claim, 6 Drawing Sheets
